UNITED STATES PATENT OFFICE

171,266

DYEING JIG

Werner P. Rose, Oakland, and Alfred R. Gessinger, Ridgewood, N. J.

Application September 21, 1953, Serial No. 26,887

Term of patent 14 years

(Cl. D55—1)

To all whom it may concern:

Be it known that we, Werner P. Rose and Alfred R. Gessinger, respectively, a citizen of the United States, residing at Valley Road, Oakland, New Jersey, and a citizen of the United States, residing at 249 Richards Roard, Ridgewood, New Jersey, have invented a new, original, and ornamental Design for a Dyeing Jig, of which the following is a specification, reference being had to the accompanying drawings, constituting a part hereof:

Fig. 1 is a front and end perspective view of a dyeing jig showing our new design;

Fig. 2 is a front perspective view with the doors open;

Fig. 3 is a front and end perspective view shown from the opposite end of that shown in Fig. 1;

Fig. 4 is a rear and top perspective view with the doors partly open.

In Figs. 2 and 4, portions are shown broken away for convenience of illustration.

This application is a continuation-in-part of

our application, Serial No. D. 11,218, filed July 15, 1950, for a Design for a Dyeing Jig.

The essential features of our design reside in the portion shown in full lines.

We claim:

The ornamental design for a dyeing jig, substantially as shown and described.

WERNER P. ROSE.
ALFRED R. GESSIONGER.
